(57) **CLAIM**

The ornamental design for a liquid spray container, as shown and described.

DESCRIPTION

FIG. 1 is a perspective view of a liquid spray container, embodying the new design;

FIG. 2 is a rear elevational view of the liquid spray container of FIG. 1;

FIG. 3 is a front elevational view of the liquid spray container of FIG. 1;

FIG. 4 is a top planar view of the liquid spray container of FIG. 1;

FIG. 5 is a side elevational view of the liquid spray container of FIG. 1, the opposite side elevational view thereof being the same; and,

FIG. 6 is a bottom planar view of the liquid spray container of FIG. 1.

The broken lines shown in the drawings are for illustrative purposes only and form no part of the claimed design.
